DESCRIPTION

The present application is related to commonly assigned U.S. patent applications Ser. Nos. 29/467,818 and 29/468,518 filed Sep. 24, 2013 and Oct. 1, 2013 respectively.

FIG. 1 is a front right perspective view of the door banner. FIG. 2 is a back right perspective view of the door banner.

FIG. 3 is a front view of the door banner.

FIG. 4 is a back view of the door banner.

FIG. 5 is a view of one side of the door banner.

FIG. 6 is a view of the opposite side of the door banner.

FIG. 7 is a top view of the door banner; and,

FIG. 8 is a bottom view of the door banner.

The present application is for the ornamental design of a door banner that wraps around a typical door as shown in the attached figures. While not part of the design, the banner generally includes a logo or image positioned on the face of the door.

The dot-dash-dot broken line circumscribing the area of the detail in FIG. 9 forms no part of the claimed design. The broken outlines of the word LOGO on the surface of the doror wrap in FIGS. 1-4 form an internal boundary. All other broken lines represent environmental structure that forms no part of the claimed design.
